UNITED STATES PATENT OFFICE.

IRVING E. ASKE, OF DULUTH, MINNESOTA.

HEATER OR VAPORIZER.

Application filed May 17, 1921. Serial No. 470,383.

To all whom it may concern:

Be it known that I, IRVING E. ASKE, a citizen of the United States, residing at Duluth, in the county of St. Louis and 5 State of Minnesota, have invented certain new and useful Improvements in Heaters or Vaporizers, of which I do declare the following to be a specification.

My invention relates to electric heater or 10 vaporizer and more particularly to the type of electric heater or vaporizer which is adapted to be interposed in a conduit for the purpose of heating or vaporizing gas or liquid during the passage of the same 15 through such conduit. It has for its object the provision of an improved and simplified structure of the type of heater or vaporizer referred to. With this and other 20 objects in view, it consists of the structures, combinations and arrangements of parts hereinafter described and claimed.

In the drawings, Fig. 1 is a side elevation of a carburetor and fuel pipe line including a gasket embodying my said invention. Fig. 2, is a front elevation of a heating element forming part of my said invention. Fig. 3, is a front elevation of a similar heating element preferably positioned so that the wires run approximately at right angles to 30 the wires in said Fig. 2. Fig. 4, is a bottom-edge plan of the frame forming part of Fig. 2. Fig. 5, is an interior or front elevation of a gasket plate adapted to contain the hereinafter described heating element, or elements. Fig. 6, is a central horizontal section through a gasket containing said heating elements. Fig. 7, is a horizontal section of said gasket on the line A—B, of Fig. 5. Fig. 8, is a diagrammatic view 40 of a normally open electric circuit, embodying said heating elements.

In the drawings, X is a carburetor of any suitable structure from which extend fuel-conducting pipe lines 1 and 2 respectively, 45 in one of which pipe lines is interposed a gasket comprising gasket plates 3 and 4. Within said gasket is positioned one or more similar heating elements each comprising a plurality of turns of wire, 5, wound upon a flat frame 6 of insulating material, preferably mica, which frame is preferably notched in two opposing edges as at 6^a to receive the wire at its turning points, and which frame has a central aperture formed therein corresponding approximately to the interior diameter of said

pipe, said aperture being crossed by said wire. The terminals of said heating element are preferably secured in any suitable manner, as by soldering, to the inner ends 60 of binding posts 7 and 8 respectively, which extend into said gasket, but if desired the hereinafter described bars may instead be connected directly to said binding posts.

It will be observed that as thus far described, the turns of said wire are in electrical as well as mechanical series, and that the winding of the wire on said frame is a very simple operation. But one of the disadvantages of such structure is that if one 70 turn of the wire is broken, the whole of the heating element is made inoperative. One of the principal features of my present invention is the transforming of said turns of wire from electric serial relationship to 75 each other to electric parallel relationship to each other. This I accomplish by bringing into contact with a plurality or all of said turns near each end of said frame, electric connecting bars 9 and 10, respectively, 80 common to said plurality of turns, whereby the several turns of said wire are electrically cross-connected and made electrically parallel to each other. Said connecting bars may be loosely positioned in said gasket, but I prefer to mould them in position when moulding the gasket plate or plates in which they are adapted to lie. Said gasket plates are of any suitable insulating material. Each of said plates has an aperture 85 11 formed therein corresponding approximately to the interior diameter of the pipe in which said gasket is interposed and has apertures 12 formed therein for the passage 90 of rivets or bolts for securing them together. 95

Preferably two of said heating elements are positioned in each gasket, in which event they are preferably positioned so that the turns of the wire of one of them extend at approximately right angles to the turns of wire of the other. Each heating element is substantially independent of and parallel to the other, both being connected to the same said binding posts; but in their preferred position at right angles to each other they cooperate to form a checker-board screen which more finely divides the current of gas or liquid and distributes the heat through it more effectually than if the turns of wire were all in one direction.

It is observed that both of said gasket plates may be recessed so that one heating

element will lie in one plate and the other heating element in the other plate, or so that one heating element may lie partly in one plate and partly in the other, but I prefer to recess only one of the plates, as 3, and to position the heating element or elements therein and to make the opposing plate 4 flat.

10 After winding the wire of the heating element upon its frame, I preferably fill the spaces between the turns of wire from the periphery of the central aperture of the frame to its outer edges, with suitable cement to prevent the collection in said spaces of moisture or particles of liquid.

15 In Fig. 8, is shown a diagram of a normally open electric circuit comprising any suitable source of electricity, as a battery 13, a normally open contact, as a starting switch 14, and two of said heating elements. If desired, other translation devices (not shown) may be interposed in said circuit. Packing strips of insulating material, as 15, 16, are preferably positioned between said 20 heating elements at the edges thereof.

25 In operation, when said circuit is closed,

gas or liquid fuel passing through said pipe line to the engine (not shown), is heated or vaporized so that it may be promptly exploded by an electric spark in a cold cylinder.

What I claim is:—

As a new article of manufacture a heating element comprising a frame of insulating material having an aperture formed therethrough for the passage of fluid, of a wire wound upon said frame, some of the turns of said wire extending across said aperture, an electric conductor extending across and in contact with a plurality of the turns of said wire near one end of said frame, and a second electric conductor extending across and in contact with a plurality of the turns of said wire near the opposite end of said frame.

40 In testimony whereof, I hereunto affix my signature, in presence of two witnesses.

45 IRVING E. ASKE.
